UNITED STATES PATENT OFFICE.

JOHN HOWARD GLASENER, OF MANSFIELD, OHIO.

JACK.

1,253,483.

Specification of Letters Patent. Patented Jan. 15, 1918.

Application filed April 7, 1917. Serial No. 160,505.

To all whom it may concern:

Be it known that I, JOHN H. GLASENER, a citizen of the United States, residing at Mansfield, in the county of Richland and 5 State of Ohio, have invented certain new and useful Improvements in Jacks, of which the following is a specification.

My invention relates to improvements in quick action jacks for use in connection with 10 automobiles or the like.

An important object of the invention is to provide means whereby a plurality of pawls is adapted to coöperate with a rack-bar, in 15 raising and lowering the same, in a highly expeditious manner.

A further object of the invention is to provide simplified means, for causing the plurality of pawls to alternately operate as raising or lowering means, for the rack-bar.

20 A further object of the invention is to provide means whereby the standard of the jack may be longitudinally adjusted, depending upon the height of the work to be raised and lowered.

25 Other objects and advantages of the invention will be apparent during the course of the following description.

In the accompanying drawings forming a part of this specification and in which like 30 numerals are employed to designate like parts throughout the same,

Figure 1 is a side elevation of a jack embodying my invention,

Fig. 2 is a horizontal sectional view taken 35 on line 2—2 of Fig. 1,

Fig. 3 is a vertical sectional view taken on line 3—3 of Fig. 4,

Fig. 4 is a horizontal sectional view taken on line 4—4 of Fig. 5,

40 Fig. 5 is a side elevation of the upper portion of the standard and housing, the side plate of the housing being removed for the purpose of illustration,

Fig. 6 is a fragmentary edge elevation of 45 the upper portion of the standard, housing, and associated elements,

Fig. 7 is a side elevation of means for preventing the separation of the standard sections,

50 Fig. 8 is a similar view of means for preventing separation of the lift bar and standard section, and,

Fig. 9 is a detail vertical section taken on line 9—9 of Fig. 1.

55 In the drawings, wherin for the purpose of illustration is shown a preferred embodiment

ment of my invention, the numeral 10 designates a standard, which is preferably longitudinally adjustable, and for this purpose the same is formed in a pair of telescoping tubular sections 11 and 12. The lower tubular section 11 is provided at its lower end with a base or foot 13, as shown. The upper vertically movable tubular section 12 is provided upon one edge with 60 ratchet teeth 14, adapted to operate within a longitudinal opening 15, formed in the lower section 11. The ratchet teeth 14 are adapted to be engaged by an upwardly swinging dog 16, rigidly secured to a rock-shaft 17, (see Fig. 2). The free end of the dog 16 contacts with the upper standard section 12, and thereby has its downward movement positively restricted. The rock-shaft 70 17 is journaled through the cylindrical portions of horizontal and vertical key hole openings 18 and 19, formed in the opposite sides of a hollow bracket 20, preferably cast integral with the lower standard section 11. At one end, the rock-shaft 17 is provided 80 with a stop shoulder 21 (see Fig. 2), and a crank 22, extending from this stop shoulder and serving to turn the rock-shaft. At its opposite end, the rock-shaft 17 is provided 85 with a lateral extension 23, which is normally inclined with respect to the key hole opening 18, thus preventing the longitudinal movement of the rock shaft toward the stop shoulder 21, which prevents the longitudinal movement of the rock-shaft in an opposite 90 direction.

As shown in Fig. 7, the lower standard section 11 is provided with a slightly inwardly bent depending tongue 24, adapted to contact with a transverse portion 25 of 95 the upper standard section 12, thus preventing the separation of the standard sections.

Preferably formed integral with the upper end of the upper standard section 12 is a housing 26, comprising lower side portions 100 27, a stationary upper side portion 28 and a removable upper side portion 29. The housing further comprises a socket 30, formed upon its upper end, and this socket has a side face 31, and the stationary upper 105 side portion 28 constitutes the opposite side face of the socket.

Mounted to reciprocate within the socket 30 and the upper standard section 12 is a rack-bar 32, provided upon its opposite 110 edges with sets of downwardly faced ratchet teeth 33.

The rack-bar 32 is provided upon its opposite sides with longitudinal grooves or depressions 34, and at the lower end of one longitudinal depression is a transverse stop 5 flange 35, (see Fig. 8) to contact with a stop finger 36 carried by one side of the socket 30 and bent inwardly therefrom. It is thus seen that means are provided to prevent the separation of the rack-bar and the socket 30. 10 At its upper end the rack-bar 32 is provided with a head or rest 37 for engagement with the load to be raised or lowered.

The upper standard section 12 is provided at its upper end with oppositely extending 15 support-brackets 38, preferably cast integral therewith. Arranged upon the opposite sides of one support bracket 38 are upwardly extending levers 39, which are pivotally connected at their lower ends, to the support 20 bracket 38, as shown at 40. Rigidly connected with the levers 39 and preferably formed integral therewith is a socket 41 for the reception of a handle or crank to operate the active parts of the jack. Arranged upon 25 the opposite sides of the other support bracket 38 are co-acting upstanding levers 42, pivoted thereto as shown at 43'. Arranged between the pairs of levers 39 and 42 are alternately acting pawls 43 and 44, 30 which are pivoted to the upper ends of these levers by means of transverse pins or pivot elements 45, also passing through and having pivotal connection with horizontal links 46, which thus serve to pivotally connect the 35 pair of levers 39 with the pair of levers 42. It is thus apparent that as the socket 41 is swung upwardly and downwardly the pawls 43 and 44 will be alternately moved in opposite directions, for raising or lowering the 40 rack-bar 32, as will be more fully explained. The pawls 43 and 44 are adapted to contact with the sets of ratchet teeth 33 and are moved into engagement therewith by a retractile coil spring 45', secured to pins 46', 45 formed upon the pawls 43 and 44.

Means are provided for controlling the action of the pawls 43 and 44, so that they will alternately raise and lower the rack-bar 32, comprising laterally extending pins 47 carried 50 by the pawls 43 and 44 and preferably formed integral therewith. These pins are arranged, as more clearly shown in Fig. 5, to contact with the upper surfaces or edges of swinging control members 48, pivoted to 55 the face 31, as shown at 49. The upper edges 50 are provided with recesses 51, thus allowing the pins to move inwardly sufficiently so that the pawls can have proper engagement with the ratchet teeth, upon 60 their up-stroke. The control members 48 are provided at their inner ends with crank extensions 52, contacting with the lower headed end of a reciprocatory stud or member 53, received by a coil spring 54, arranged 65 within a socket 55. It is thus apparent that

yielding means are provided to retain the control members 48 in the active position with their edges 50 approximately horizontal.

Means are provided to lock the control 70 members 48 in the inactive position, so that their edges 50 will be arranged in a lower inclined position and practically out of contact with the pins 47, and if contacting therewith, in no way influencing the operation 75 of the pawls. Such means comprises a cam 55', (see Figs. 5 and 9) formed upon a rock-shaft 56, one end of which is pivoted in an opening 57 in the face 31, and the opposite end is pivoted in an opening 58 in the 80 plate 29. This rock-shaft is turned by a crank 59 rigidly secured thereto. When the crank 59 is in an approximately horizontal position, and extending to the right, as shown in Fig. 1, the cam is in the lower 85 position, (see Fig. 5) and when this crank is swung to the left to assume an approximately horizontal position, the cam is raised, contacting with the crank extensions 52 of the control members 48, thus retaining the 90 edges 50 in the lower or inactive position.

The operation of the jack is as follows:

When the crank 59 is moved to the approximately horizontal position to the left, the edges 50 of the control levers 48 are in 95 the lowermost position, and do not act upon the pins 47 sufficiently to influence the action of the pawls 43 and 44. These pawls alternately engage the teeth 33 and accordingly raise the rack-bar 32, when the socket 100 41 is swung up and down. When the crank 59 is swung to the right, the cam 55' moves out of contact with the crank extensions 52, and the spring 54 and associated elements 105 yieldingly retain the control members 48 in the active position, the edges 50 then being in the uppermost position. When the socket 41 is now raised and lowered, the pawls 43 and 44 are alternately moved into engagement with the ratchet teeth 33. When the 110 socket 41 is moved upwardly, the pawl 43 makes its up stroke, to engage beneath the next ratchet tooth 32. The pawl 44 is simultaneously making its down stroke, and the pin 47 thereof is traveling in contact with 115 the edge 50. When the pawl 43 moves up sufficiently to take the entire load of the rack-bar 32 the yieldingly held control lever 48 will act upon the pin 47 of the pawl 44 and moves the pawl upwardly out of engagement with the ratchet tooth which it last engaged. When the socket 41 is swung 120 downwardly the pawl 44 upon its up stroke, does not engage this last engaged ratchet tooth but the next ratchet tooth thereabove, 125 thus allowing the rack-bar to descend for one tooth, when the pawl 43 partakes of its down stroke. The action of the pawl 43 upon its upstroke is similar to that of the pawl 44 and therefore need not be further 130

described. It is thus apparent that the up and down swinging movement of the socket 41 will effect a step by step lowering movement of the rack bar 32.

5 It is understood that the form of my invention herewith shown and described is to be taken as a preferred example of the same, and that various changes in the shape, size, and arrangement of parts may be resorted 10 to without departing from the spirit of the invention or the scope of the subjoined claims.

Having thus described my invention, I claim:

15 1. In a jack of the character described, a standard, a lift bar having slideable engagement therewith and provided upon its opposite edges with longitudinal sets of teeth, a plurality of pawls disposed outwardly of 20 and near the opposite edges of the lift bar and connected with the standard, means to alternately raise one pawl and lower the other, control members pivotally connected with one side of the standard and extending 25 outwardly and laterally beyond the edges of the lift bar to be arranged in proximity to the ends of the pawls, pins carried by the pawls and contacting with the control members, yielding means normally engaging the 30 inner portions of the control members to normally retain them in the active position, and means to hold the control members in the inactive position.

2. In a jack of the character described, a 35 tubular standard, a lift bar mounted to reciprocate within the tubular standard and provided upon its opposite edges with teeth, a plurality of pawls pivotally connected with the opposite edges of the tubular standard and arranged near and outwardly of the 40 opposite edges of the lift bar to engage with

the teeth thereof, means to alternately raise one pawl and lower the other, control members pivoted at spaced points with the tubular standard and extending laterally and 45 outwardly beyond the tubular standard and the opposite edges of the lift bar for substantial distances, pins carried by the pawls and contacting with the control members, crank extensions carried by the inner ends of 50 the control members and extending inwardly beyond the pivots thereof, a pressure member engaging the crank extensions to move them downwardly, yielding means to move the pressure element downwardly, and 55 a cam pivoted to the tubular standard and disposed beneath the crank extensions to engage therewith and move the same upwardly.

3. In a jack of the character described, 60 the combination with a standard, including a pair of telescoping standard sections, a hollow bracket carried by one standard section and provided upon its opposite sides with key hole openings, a rock-shaft pivoted 65 within the round portions of the key hole openings and provided at one end with a stop member and at the opposite end with a lateral extension, means to turn the rock-shaft, a pawl carried by the rock-shaft and 70 adapted to pass through one key hole opening, teeth formed upon the other standard section and adapted to be engaged by the pawl, a lift bar slideably engaging one standard section, and means to raise and lower 75 the lift-bar.

In testimony whereof I affix my signature in presence of two witnesses.

JOHN HOWARD GLASENER.
